SLIP COVERING FOR ARMCHAIRS

Rudolf Siebelist, Bronx, N. Y.

Application June 19, 1947, Serial No. 755,704

5 Claims. (Cl. 155—182)

1

This invention relates to chair covers.

It is an object of the present invention to provide a chair cover which can be easily slipped over an open arm chair and over the arms of the same. These covers will be fastened together at the seat level below the arm of the chair and at the back from the seat to the level of the arm. Thus the seat covers can be adjusted to the chair with a minimum of effort and without interference from the arms.

This method of construction eliminates bulky seams, gaping border openings and provides the means of keeping the finished article smooth and well matched.

Other objects of the present invention are to provide a seat cover which is of simple construction, inexpensive, less tedious and quicker to manufacture and convenient to use.

According to the invention, the seat cover is formed to fit the seat and the back of the chair and at the locations where the arms of the chair are projected, there are provided openings whereby the seat cover can be slipped downwardly over the arms of the chair to the level of the seat, thus leaving the arms of the chair exposed. Once the seat cover has been disposed over the chair, the fastening means of the opening through which the arms of the chair were extended are fastened together to finally fit the cover tightly about the chair. The fastening means will extend along the side edge of the rear of the seat and upwardly to the elevation of the chair arm. The fastening means may take the form of snaps, snap tape, "zippers" or any other common means which are employed with seat covers.

In a modified form of the invention, a piece of loose material which may be stretched is provided about the portion of the opening which extends about the bottom of the arm rests whereby to provide a sealing engagement with the arm rests to prevent articles or other matter from getting under the seat cover so as to stain or damage the chair.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a chair with the seat cover embodying the features of the present invention disposed thereon.

Fig. 2 is a fragmentary view of the seat cover

2

looking upon the inside of the exterior wall portion of the cover about the opening.

Fig. 3 is an enlarged cross sectional view taken in the region of the arm opening of the cover.

Fig. 4 is an enlarged fragmentary perspective view of the seat cover looking upon the opening with the fastening elements about to be brought together to close the opening.

Fig. 5 is a fragmentary view of the seat cover in which there is provided in the portion of the opening adapted to extend about the arm material which can be stretched tightly about the arm whereby to prevent articles from getting beneath the cover.

Fig. 6 is a fragmentary perspective view of the portion of the opening of the cover and of the elastic closure means therein.

Fig. 7 is a cross sectional view taken on line 7—7 of Fig. 6.

Referring now to the figures, 10 represents a chair over which a slip cover 11 bearing the features of the present invention is extended. This chair has arms 12 with vertical supports 13 extending from the seat portion of the chair to support the outer ends of the arms. The seat cover is made so that the same can be slipped from the top of the chair downwardly and is provided with openings at the sides and rear, as indicated at 14, through which the arm portions and supports are extended so that the opening will lie at the base of the arm portions and at the seat level.

On the back part of the seat cover and adapted to extend around the side edge thereof beneath the arm 12 is a projection 15 having snap fastener elements 16 thereon. This projection is fastened in place by cooperating snap fastener elements 17 on the back wall of the cover. Piping 18 extends about the top of the projection 15 and upwardly around the inner end of the arm. This piping is extended about the slip cover to add to its appearance.

On the seat portion of the cover, there is extended downwardly a flange 19 (Fig. 3) on which are disposed snap fastener elements 21. At the exterior of the opening, there is provided on border material 22, cooperating snap fastener elements 23 which unite with the elements 21 to finally close the arm opening 14. About the portion of the opening which extends about the base of the arm support 13, there is provided piping 24.

Referring now particularly to Figs. 5, 6 and 7, there is shown provided about that portion of the opening 14 which extends about the bottom

of the arm support 13, elastic material 26 adapted to be wrapped tightly about the bottom of the arm support whereby to effectively close the space outwardly of the piping 24. An elastic 27 may extend through the folded edge of the material 26, as shown in Fig. 7.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a chair having a seat and a back with an arm extended forward from said back and supported at its front end by a support extended vertically from the seat, a one-piece cover for the chair having a back enclosing portion, a seat covering portion and a flounce portion depending from said seat covering portion, said back enclosing portion being formed with an opening through which the rear end of the arm extends, said seat covering portion being formed with an opening through which the bottom end of the support extends, said cover being formed with a slit extended rearward along said seat covering portion from said opening through which the support extends and upward along said back enclosing portion to said opening through which the arm extends permitting the arm and support to be extended from said cover when it is positioned on the chair, and means for holding the slit closed while said cover is in position on the cover.

2. In combination with a chair having a seat and a back with an arm extended forward from said back and supported at its front end by a support extended vertically from the seat, a one-piece cover for the chair having a back enclosing portion, a seat covering portion and a flounce portion depending from said seat covering portion, said back enclosing portion being formed with an opening through which the rear end of the arm extends, said seat covering portion being formed with an opening through which the bottom end of the support extends, said cover being formed with a slit extended rearward along said seat covering portion from said opening through which the support extends and upward along said back enclosing portion to said opening through which the arm extends permitting the arm and support to be extended from said cover when it is positioned on the chair, and means for holding the slit closed while said cover is in position on the cover, said means comprising complementary snap fastener elements mounted on the material of said cover on opposite sides of said slit.

3. In combination with a chair having a seat and a back with an arm extended forward from said back and supported at its front end by a support extended vertically from the seat, a one-piece cover for the chair having a back enclosing portion, a seat covering portion and a flounce portion depending from said seat covering portion, said back enclosing portion being formed with an opening through which the rear end of the arm extends, said seat covering portion being formed with an opening through which the bottom end of the support extends, said cover being formed with a slit extended rearward along said seat covering portion from said opening

through which the support extends and upward along said back enclosing portion to said opening through which the arm extends permitting the arm and support to be extended from said cover when it is positioned on the chair, and means for holding the slit closed while said cover is in position on the cover, and means for closing the spaces between the edges of said seat covering portion defining said opening through which the support extends and the adjacent faces of the support.

4. In combination with a chair having a seat and a back with an arm extended forward from said back and supported at its front end by a support extended vertically from the seat, a one-piece cover for the chair having a back enclosing portion, a seat covering portion and a flounce portion depending from said seat covering portion, said back enclosing portion being formed with an opening through which the rear end of the arm extends, said seat covering portion being formed with an opening through which the bottom end of the support extends, said cover being formed with a slit extended rearward along said seat covering portion from said opening through which the support extends and upward along said back enclosing portion to said opening through which the arm extends permitting the arm and support to be extended from said cover when it is positioned on the chair, and means for holding the slit closed while said cover is in position on the cover, and a piece of elastic material projected across said opening in said seat covering portion through which the support extends, and stitches securing the front, rear and inner edges of said piece of elastic material to the adjacent edges of said seat covering portion defining said opening through which the support extends leaving the outer edge of said elastic material free to adjust itself to the shape of the support to close the spaces between the edges of said seat covering portion defining said opening through which the support extends and the adjacent faces of the support.

5. In combination with a chair having a seat and a back with an arm extended forward from said back and supported at its front end by a support extended vertically from the seat, a one-piece cover for the chair having a back enclosing portion, a seat covering portion and a flounce portion depending from said seat covering portion, said back enclosing portion being formed with an opening through which the rear end of the arm extends, said seat covering portion being formed with an opening through which the bottom end of the support extends, said cover being formed with a slit extended rearward along said seat covering portion from said opening through which the support extends and upward along said back enclosing portion to said opening through which the arm extends permitting the arm and support to be extended from said cover when it is positioned on the chair, and means for holding the slit closed while said cover is in position on the cover, and a piece of elastic material projected across said opening in said seat covering portion through which the support extends, and stitches securing the front, rear and inner edges of said piece of elastic material to be adjacent edges of said seat covering portion defining said opening through which the support extends leaving the outer edge of said elastic material free to adjust itself to the shape of the support to close the spaces between the edges of said seat covering portion defining said

opening through which the support extends and the adjacent faces of the support, and a reinforcing and stiffening elastic mounted along the free outer edge of said piece of elastic material.
